(No Model:)

J. T. BENDER.
PLOW WHEEL.

No. 445,282.

Patented Jan. 27, 1891.

UNITED STATES PATENT OFFICE.

JOHN T. BENDER, OF CANTON, OHIO.

PLOW-WHEEL.

SPECIFICATION forming part of Letters Patent No. 445,282, dated January 27, 1891.

Application filed October 1, 1890. Serial No. 366,709. (No model.)

To all whom it may concern:

Be it known that I, JOHN T. BENDER, a citizen of the United States, residing at Canton, in the county of Stark and State of Ohio, have 5 invented certain new and useful Improvements in Plow-Wheels; and I do hereby declare that the following is a full, clear, and exact description of the same, reference being had to the annexed drawings, making a part 10 of this specification, and to the letters marked thereon, in which—

Figure 1 is a view showing the wheel properly attached to a plow. Fig. 2 is a section of the wheel showing its different parts. Fig. 15 3 is a detached view of the head. Fig. 4 is a top view of the head, showing section of the wheel-arm. Fig. 5 is a view showing a portion of the wheel-hub and its thimble. Fig. 6 is a view of the wheel and its different parts 20 detached from a plow-beam. Fig. 7 is a detached view of the thimble.

The present invention has relation to plow-wheels; and it consists in the different parts and combination of parts hereinafter described, and particularly pointed out in the 25 claims.

Similar letters of reference indicate corresponding parts in all the figures of the drawings.

30 In the accompanying drawings, A represents the wheel-arm, which is semicircular in cross-section, and is so formed for the purpose hereinafter described.

The head B is substantially of the form 35 shown in the drawings, and as shown it is provided with the groove a, which is for the purpose of receiving the bottom or under side of a plow-beam. The head B is provided with the semicircular portion b, which is received into

40 the semicircular arm A, as shown in Figs. 4 and 6. The head B is securely held to the arm A by means of the clamping-bolt c, and for the purpose of adjusting the arm A, together with the wheel C, up and down, the elongated slot

45 d is provided. For the purpose of adjusting the arm A, together with the wheel C, at any desired angle with reference to the plow-beam, the slot e is provided, thereby allowing the arm A to turn on the semicircular portion b.

50 The head B is securely clamped to the end

of a plow-beam by means of the clamping-bolts f and the bar g.

The recess D is for the purpose of receiving the bottom or lower end of one of the clamping-bolts f, and for the purpose of easily 55 detaching the head B, together with its different parts, and at the same time preventing the necessity of detaching the clamping-bolt f from the bar g. The recess D is open, as illustrated in Fig. 3, and for the purpose 60 of holding the bolt f received by the recess D the ears h are provided, and are located upon the under side of the head B.

Within the hub E is located the box F, and for the purpose of causing the box F to rotate with the wheel C and its hub E said box is provided with the lug h', which lug is received into the recess h². Within the box F is located the thimble H, which thimble is formed somewhat longer than the box F, for 70 the purpose of leaving the hub E free to rotate with the box F. For the purpose of holding the arm end of the thimble H in proper position, the collar I is formed upon the side of the arm A, and is located as illustrated in 75 Fig. 2. The opposite end of the thimble H is held in proper position by means of the cap J, which cap embraces the end of the box F, as illustrated in Fig. 2. The thimble H is provided with the flange K, which abuts 80 against the arm A. The opposite end of the thimble H abuts against the cap J. It will be seen that by my peculiar arrangement dirt cannot reach the bearing portion of the thimble H. The clamping-bolt L is for the 85 purpose of attaching the wheel C, together with the different parts, to the arm A.

In Fig. 2 the bolt L is shown with the nut against the cap J; but in use the head of the bolt should come against the cap, as illustrated in Fig. 6.

Having fully described my invention, what I claim as new, and desire to secure by Letters Patent, is—

1. The combination of the arm A, formed 95 semicircular in cross-section, the head B, provided with the semicircular portion b, the slot e, the clamping-bolt c, the clamping-bolt f, the bar g, and the wheel C, substantially as and for the purpose set forth.

2. The combination of the arm A, the thimble H, the box F, located around said thimble and provided with the lug h' , the hub E, provided with the recess h^2 , the collar I, the cap J, the clamping-bolt L, and means for adjusting the wheel C, substantially as and for the purpose specified.

3. The combination of the arm A, the head B, provided with the recess D, the ears h , the

clamping-bolts f, and the bar g, substantially as and for the purpose set forth.

In testimony that I claim the above I have hereunto set my hand in the presence of two witnesses.

JOHN T. BENDER.
